UNITED STATES PATENT OFFICE.

EDWIN P. WANNER, OF NEW YORK, N. Y.

DESIGN FOR AN ARM-CHAIR.

41,617.

Specification for Design.

Patented July 25, 1911.

Application filed March 10, 1910. Serial No. 548,506. Term of patent 14 years.

To all whom it may concern:

Be it known that I, EDWIN P. WANNER, a citizen of the United States, residing in New York city, county of New York, and State of New York, have invented a new, original, and ornamental Design for Arm-Chairs, of which the following is a specification, reference being had to the accompanying drawing, forming part hereof.

The drawing represents a perspective view of the chair.

The standards *c*, comprising back legs *d* extending below the seat and uprights *e* extending above the seat, are bent inwardly relatively to the seat and each is rectangular and of uniform dimensions cross-sectionally from end to end thereof.

The structure *f*, forming the back and arms of the chair, is substantially U-shaped in plan, the open sides thereof being toward the front. At the back, said structure surrounds the uprights *e* and is itself surrounded by the extension *g* which is curved in plan to conform with the curvature of the back of said structure as seen in plan, and which is rounded off at the top, as seen

in front or rear elevation. The forward portions of said structure *f* are bent first downwardly and back in curves *h* and then downwardly again, as at *i*, their extremities being joined with the seat. The structure *f* is substantially rectangular and of uniform dimensions in cross-section from end to end thereof. The brace *j* is also substantially U-shaped in plan, its open side being toward the rear. Its front portion *k* connects the front legs *b*, while its ends *l* are curved upwardly to the seat at points between the front and back legs and then downwardly, where each of the extremities of the structure *j* is joined to a back leg *d*.

I claim:

The ornamental design for a chair as shown and described.

In testimony, that I claim the foregoing I have hereunto set my hand this eighth day of March, 1910.

EDWIN P. WANNER.
